(57) **CLAIM**

The ornamental design for a soldering iron, as shown and described.

DESCRIPTION

FIG. 1 is a top perspective view of a first embodiment of a soldering iron;

FIG. 2 is a bottom perspective view of the soldering iron of FIG. 1;

FIG. 3 is a top view of the soldering iron of FIG. 1;

FIG. 4 is a side elevational view of the soldering iron of FIG. 1;

FIG. 5 is a bottom view of the soldering iron of FIG. 1;

FIG. 6 is a front elevational view of the soldering iron of FIG. 1;

FIG. 7 is a rear elevational view of the soldering iron of FIG. 1;

FIG. 8 is a top perspective view of a second embodiment of a soldering iron;

FIG. 9 is a bottom perspective view of the soldering iron of FIG. 8;

FIG. 10 is a top view of the soldering iron of FIG. 8;

FIG. 11 is a side elevational view of the soldering iron of FIG. 8;

FIG. 12 is a bottom view of the soldering iron of FIG. 8;

FIG. 13 is a front elevational view of the soldering iron of FIG. 8; and,

FIG. 14 is a rear elevational view of the soldering iron of FIG. 8.

The broken line portions of the disclosure illustrate unclaimed structure.
